GLASS JAR TOP

Ray E. Kendall and June E. Kendall, Los Angeles, Calif.

Application April 28, 1958, Serial No. 50,633

Term of patent 14 years

(Cl. D58—26)

Fig. 1 is a side elevational view a self-measuring pouring spout glass jar top shown in closed position and showing our new design;

Fig. 2 is a top plan view thereof;

Fig. 3 is a side elevational view thereof shown in open position;

Fig. 4 is a bottom plan view thereof; and

Fig. 5 is a bottom perspective view thereof.

The characteristic features of our design for the self-measuring pouring spout glass jar top disclosed reside in the pattern of ornamentation disposed thereon having the configurations shown.

We claim:

The ornamental design for a self-measuring pouring spout glass jar top, substantially as shown and described.
